ATTACHMENT FOR FILING DRAWERS

Filed Feb 20, 1929

2 Sheets-Sheet 2

UNITED STATES PATENT OFFICE

ROY H. CHARLTON, OF BELMONT, MASSACHUSETTS, ASSIGNOR TO FILING EQUIPMENT BUREAU, INCORPORATED, OF BOSTON, MASSACHUSETTS, A CORPORATION OF MASSACHUSETTS

ATTACHMENT FOR FILING DRAWERS

Application filed February 20, 1929. Serial No. 341,343.

This invention relates to filing devices such as drawers or trays for use in vertical filing systems, and pertains more particularly to means adapted to be removably attached to 5 a filing drawer or box for holding the indexed cards, sheets or folders in an upright position and for facilitating the inspection of the filed contents and the removal of the same from the drawer. The subject matter hereinafter particularly described and 10 claimed constitutes an improvement upon the devices disclosed and the inventions claimed in my copending application for filing devices, Serial No. 212,794, filed August 13, 15 1927.

In said copending application I have illustrated and described an attachment mounted upon the side walls of a filing drawer and comprising essentially guide members extending lengthwise of the drawer at each side, panel-supporting members or riders 20 slidably mounted for movement longitudinally of the guide members, transverse panels or partition members removably carried between opposite riders or slides, and spring members on the guides and bearing against the slides to permit independent lengthwise movement of the slides, but to restrain said movement so that the panels are normally 25 supported in spaced parallel relation transversely of the drawer.

While the devices shown and described in 30 said application satisfactorily perform their intended functions and constitute meritorious advances in the art of vertical filing, the apparatus embodying the present invention is 35 a distinct and desirable improvement upon the former structures, particularly in its simplicity of construction and assemblage, and its adaptability for ready attachment, without the use of screws, bolts or similar fastenings, upon filing drawers or trays. It is a 40 particular feature of the improved device that the assembly may be manufactured in a 45 relatively small number of sizes for particular types of filing drawers and that an attachment having a selected size may be properly fitted to all drawers of the same general size irrespective of slight variation in the lengths 50 of drawers made by different manufacturers.

The accompanying drawings illustrate a recommended embodiment of the present invention with optional variations in structure to permit attachment of the assembly upon slightly different types of filing drawers. In 55 the drawings,

Fig. 1 is a plan view of one type of drawer equipped with the improved attachment;

Fig. 2 is a side elevation thereof with the drawer shown in broken lines;

Fig. 3 is an enlarged section on the line 3—3 of Fig. 1;

Figs. 4, 5 and 6 are enlarged fragmentary sections on the lines 4—4, 5—5 and 6—6 respectively of Fig. 2; and

Fig. 7 is a sectional view looking toward the forward end of another type of drawer, showing a modified form of connection at the front of the attachment.

The improved device may be applied to any 70 style of filing drawer having the customary side walls upon which the assembly supports are preferably mounted, and in one of its recommended forms is especially adapted to the type of sheet-metal drawer shown in 75 Figs. 1 and 2, in which the front end 8 of the drawer is provided with rearwardly projecting, vertical fins 9. Such a drawer customarily has side walls 10 formed with a rolled-over upper edge 11, and a rear wall 12, 80 usually lower than the front wall.

The assembled attachment for a drawer of 85 this type (Figs. 1 to 6) preferably comprises a pair of vertically spaced guide rails 13 mounted above each side wall 10 and extending lengthwise of the drawer substantially in 90 the plane of said walls; rail supports 14 at the front and 15 at the rear of the drawer, each having a pair of sleeves 16 and 17, respectively, receiving the front and rear ends of the guide rods 13, and preferably having flanges 18 and 19 respectively resting upon the doubled upper edges 11 of the side walls 10; panel-supporting members or slides 20 mounted on the respective pairs of guide 95 members, each slide or rider having upper and lower sleeve portions 21 receiving the guide rods 13, whereby the riders may slide longitudinally along the guides, and preferably having longitudinally spaced, vertical 100

slots 22 disposed between the sleeves 21; transverse panels 23 for dividing the drawer space into several compartments, each panel having side wings 24 removably received within corresponding slots 22 of opposite slides 20 to support the panel or partition within the drawer; and springs 25 surrounding a guide rod of each pair and having their ends normally bearing directly or indirectly against the opposite ends of the slides to restrain sliding movement thereof, so that the panels 23 are normally supported in spaced parallel relation. Filed cards, sheets or folders placed within the drawer will accordingly be maintained in upright position by the flexibly mounted panels defining the respective drawer compartments, and the compartments are capable of ready expansion or contraction when it is desired to inspect the filed subject matter or to insert or remove the files.

The guide rails 13 preferably are round metal rods, and the rail supports 14 and 15 preferably consist of metal plates riveted or otherwise securely fastened together as at 26, the outer of said plates being shaped to form the sleeves 16 or 17 and the bottom flange 18 or 19. The sleeves of one pair at least of said supports, for example the supports 15, are preferably open at both ends and fit snugly around the rods 13 frictionally to resist relative lengthwise movement between the members, whereby the position of said supports may be adjusted longitudinally according to the length of the drawer; whereas the outer ends of the sleeves 16 of the front supports 14 may be closed as indicated at 27, if desired.

The forward ends of the two plates 28, 29 (Figs. 5 and 6) constituting each front support 14 may be slightly spread apart to provide resilient gripping jaws 30 and 31 receiving and frictionally clamping upon the drawer fins 9, removably to secure said supports in position upon the drawer. The outer plates 32 of the rear supports 15 are formed in substantially the same manner as plates 28 to furnish the sleeves 17 and the flanged rests 19, the sleeves being open-ended as aforesaid; and the inner plates 33 of said supports extend downwardly to bear against the inner surfaces of the side walls 10, as best shown in Fig. 3. The rearward ends of the plates 33, which may abut the rear wall 12 of the drawer, are preferably returned inwardly to provide vertical sleeves 34 frictionally retaining the legs of a resilient U-shaped expander rod 35. Said rod legs tend to spring outwardly, thereby forcing the plates 33 against the drawer walls 10, frictionally to retain the guide rail supports 15 upon said walls. The rod preferably extends across the drawer above the rear wall 12 to serve as a back rest for the filed material.

Each panel carrier or slide 20 may consist of a metal strip having its longitudinal mar-

gins rolled over outwardly to furnish its tubular sleeves 21 which loosely receive the guide rods 13, so that the carriers may freely slide along the rods, and one or more vertical slots 22 may be provided in the body of the metal sheet, as aforesaid, three such slots being illustrated in each slide to permit initial longitudinal adjustment of the panel positions.

The panels 23 may be formed of metal, wood, cardboard or other sheet material and are preferably provided with reinforcing metal strips 36 affixed flatwise to the panels by suitable fastening means. Laterally projecting ends of the strips 36 may constitute the panel-supporting wings 24, as shown, and the tips of said wings are preferably bent transversely, as indicated at 37, to prevent accidental removal of the tips from the slide slots 22 as the slides are moved along the guide rods. The wing tips of each panel preferably are bent in opposite directions so that a panel may readily be detached from its supporting slides by swinging it obliquely of the drawer, as indicated by the broken line 90 position 37 of Fig. 1, thereby permitting the wings to be withdrawn from the slots 22.

The springs 25 may be formed of wire coils, and cupped collars 38 preferably receive the ends of the coils. The spring ends may be secured within the collars 38, and the collars normally bear against the slides 20 or, at the ends of the assembly, against the rail mountings 14 or 15. Preferably the collars are free to slide independently of the slides 20, so that the springs are not stretched upon extreme movement of the slides.

Fig. 7 illustrates a modified form of construction for mounting the forward end of the attachment upon a drawer or tray of the type having a plain faced front wall 38 without projecting fins. The mounting structure in such case may comprise supports 39 formed substantially as are the rear supports 15 of Figs. 1 to 6, and resting on the side walls 40 as before; and a spring rod or expander 41 similar to rod 35 and operating in the same manner frictionally to hold the supports 39 in fixed position. In this modification, however, the rod legs preferably extend upwardly through the sleeves of the support, as shown, in order that the lower portion of the legs may also bind against the side walls, with the transverse portion of the rod disposed near the bottom of the drawer. Obviously, this form of front mounting may also be employed with the finned-front type of drawer, and may be used at the back of the drawer, if desired.

An attachment constructed as above described is economical to manufacture, simple to assemble and disassemble, as there is no fixed connections between its component members, and easy to mount in properly adjusted position upon a filing drawer, irrespective of its 130

precise longitudinal dimension; and when so mounted the structure is compact and rigid, does not interfere with filing or limit the filing space within the drawer, and furnishes 5 flexibly mounted partitions which may readily be adjusted at the desired longitudinal intervals to support the filed subject matter in vertical position. It will be understood, however, that structural details may be varied to 10 suit particular purposes without departing from the essence of this invention as defined in the following claims.

I claim:

1. A filing device comprising, in combination with a drawer, guide rails extending longitudinally of the drawer at each side thereof, means for supporting the guide rails upon the walls of the drawer, means cooperating with the supporting means and with the drawer for 20 frictionally retaining the rails in said supported position against casual displacement, slides mounted on said rails and movable longitudinally thereof, a panel for dividing the drawer space carried by opposite slides, and 25 springs on the respective rails adapted to restrain movement of the slides.

2. A filing device comprising, in combination with a drawer, guide rails extending longitudinally of the drawer at each side thereof, supports for the respective ends of the rails on the walls of the drawer, resilient means 30 cooperating with said supports and said drawer for frictionally retaining the supports in position, slides mounted on each guide rail 35 for independent longitudinal movement, panels for dividing the drawer space supported between opposite slides, and springs carried by the respective rails and bearing on the slides to restrain said movement.

3. A filing device comprising, in combination with a drawer, guide rails extending longitudinally of the drawer at each side thereof, supports for the respective ends of the guide rails mounted on the side walls of the drawer, 45 the supports at one end at least of the device being movable along the guide rails and including means for holding the supports in a predetermined position with respect to the rails, slides mounted on each guide rail for 50 independent longitudinal movement, panels for dividing the drawer space supported between opposite slides, and springs carried by the respective rails and bearing on the slides to restrain movement of the slides.

4. A filing device comprising, in combination with a drawer, guide rails extending longitudinally of the drawer at each side thereof, supports for the respective ends of the rails removably mounted on the side walls 60 of the drawer, means associated with said supports and frictionally engaging the walls of the drawer to hold the supports in position, the supports at one end at least of the device having sleeves frictionally receiving 65 the rails whereby the position of the supports

may be adjusted longitudinally of the rails, slides mounted on each guide rail for independent longitudinal movement, panels for dividing the drawer space suspended between opposite slides, and springs mounted on the rods between the slides to restrain movement 70 of the slides.

5. A filing device comprising, in combination with a drawer, a pair of guide rods extending longitudinally of the drawer in vertically spaced, parallel relationship substantially in the plane of the side walls of the drawer, supporting members removably connected with the respective ends of the guide rods and detachably mounted upon said side walls, the supporting member at the front ends of the guide rods having frictional engagement with the drawer, an expander rod bearing against the supporting members at the rear end of the guide rods thereby frictionally to hold said members in position against the side walls of the drawer, slides mounted for longitudinal movement upon the respective pairs of guide rods, panels for dividing the drawer space detachably suspended from opposite slides, and springs mounted upon one rod at least of each pair between said slides to restrain longitudinal movement of the slides.

6. A filing device comprising, in combination with a drawer, a pair of guide rods extending longitudinally of the drawer in vertically spaced, parallel relationship substantially in the plane of the side walls of the drawer, supports for detachably mounting the front ends of the rods upon said side walls, other supports for the rear ends of the rods, said rear supports having open-ended sleeves frictionally receiving the rods whereby the position of said supports may be adjusted 95 longitudinally of the rods, and having depending portions bearing against the inner sides of the respective walls, an expander extending across the drawer and engaging the rear supports to press said depending portions against the walls, thereby frictionally to secure the rear supports in attached position, slides mounted for longitudinal movement upon the respective pairs of guide rods, panels for dividing the drawer space suspended between opposite slides, and springs mounted on one rod at least of each pair to restrain longitudinal movement of the slides.

7. A filing device comprising in combination with a drawer having fins projecting inwardly from its front wall, a pair of guide rods extending longitudinally of the drawer in vertically spaced, parallel relationship substantially in the plane of the side walls of the drawer, supporting plates for detachably mounting the front ends of the rails upon said side walls, said plates having frictional engagement with said fins, other supports for the rear ends of the rails, said rear supports having sleeves frictionally receiving 120 125 130

- the rods whereby the position of said supports may be adjusted longitudinally of the rods, and having depending portions bearing against the inner sides of the respective walls, an expander extending across the drawer and
5 engaging the rear supports to press said depending portions against the walls, thereby frictionally to secure the rear supports in attached position, slides mounted for longitudinal movement upon the respective pairs
10 of guide rods, panels for dividing the drawer space suspended between opposite slides, and springs mounted on one rod at least of each pair to restrain longitudinal movement of the slides.
